UNITED STATES PATENT OFFICE.

GEORGE A. REICH, OF SAN FRANCISCO, CALIFORNIA.

SEWER-TRAP.

SPECIFICATION forming part of Letters Patent No. 278,045, dated May 22, 1883.

Application filed February 7, 1883. (No model.)

To all whom it may concern:

Be it known that I, GEORGE A. REICH, of San Francisco, in the county of San Francisco and State of California, have invented certain new and useful Improvements in Sewer-Traps, of which the following is a specification.

This invention has reference to an improved sewer-trap of that class which is interposed between the house-main and the sewer; and the invention consists of a sewer-trap formed of a U-shaped pipe having a central upright casing. Within the upright casing is arranged a removable receptacle with an inclined perforated bottom for oakum saturated with carbolic acid. The receptacle is guided by diametrical flanges in the grooves of the cylindrical case, and provided at the lower end with hinged valves that fit on seats of the U-shaped pipe.

In the accompanying drawings, Figure 1 represents a vertical longitudinal section of my improved sewer-trap. Fig. 2 is a horizontal section of the trap on line $\alpha\alpha$, Fig. 1; and Fig. 3 is a vertical transverse section of the same, showing the interior receptacle.

Similar letters of reference indicate corresponding parts.

A in the drawings represents a U-shaped pipe, which connects at one side with the main pipe that leads from the house, and at the other side with the pipe leading to the sewer. The U-shaped pipe A is provided with a central upright casing, B, of cylindrical shape, within which is arranged a receptacle, C, preferably of cylindrical shape, with flattened sides, as shown in Fig. 2, that is open at the top and provided with a conical perforated bottom, as shown clearly in Fig. 1. The receptacle C is guided by flanges $a a$, arranged at diametrically-opposite points in interior grooves, a' , of the casing B.

To the lower part of the receptacle C, below the flanges $a a$, are hinged two valves, D D', the former of which is fitted on an interior seat, d , of that part of the pipe A communicating with the house-pipe, while the valve D' fits on an interior seat, d' , of that part of the pipe A connected to the sewer-main.

For the purpose of placing the receptacle C and the valves D D' into their proper posi-

tions, the casing B is provided with interior guide-shoulders and grooves, d^2 , at that side where the valve D' is arranged, said guides slanting over at their lower ends toward the seat d' , so that the valve D' can pass along the latter into position without obstruction. The valve D assumes at the same time its position on the seat d . Both valves turn on their hinges in the direction toward the sewer, as indicated by arrows in Fig. 1, both being retained in position on their seats by the pressure of the liquid in the trap. At the lower end of the casing B are arranged inwardly-projecting shoulders $e e$, on which the flanges $a a$ of the receptacle C are supported. A center rod, f, which is connected to the bottom of the receptacle C, passes through a central opening of the lid B' of the case B, and serves to screw the lid tightly in position by a nut, f'. The receptacle C is filled with oakum charged with carbolic acid, which neutralizes the sewer-gases and other vapors emitted by the water in the trap. Whenever a new charge of carbolic acid has to be given, or a new supply of oakum, the lid is removed, while about once a month, or oftener, the receptacle is entirely removed and the trap flushed with water and thoroughly cleaned of all sediments.

By my improved sewer-trap the sewage from the house will readily pass to the main sewer, as the valves will open and close in accordance with the pressure of the liquid thereon. When the sewage is discharged they are closed by the body of the liquid remaining in the U-shaped body of the trap, so as to form thereby a double seal that prevents the passage of sewer-gases into the house.

Having thus described my invention, I claim as new and desire to secure by Letters Patent—

1. A sewer-trap consisting of a U-shaped main pipe, A, a central cylindrical casing, B, and an interior removable receptacle, C, having valves D D', hinged to the lower part thereof, and fitted on interior seats, $d d'$, of the main pipe A, substantially as set forth. 95

2. The combination of a U-shaped main pipe, A, a central upright casing, B, an interior removable receptacle, C, that is guided in the casing, and provided with a perforated bottom, and hinged valves D D', that open in 100

the same direction toward the sewer, and are fitted to interior seats of the main pipe A, substantially as specified.

3. The combination of the U-shaped main pipe A, having an upright cylindrical casing, B, the latter being provided with interior guide-grooves, a' , and guide-shoulders d^2 , with a detachable receptacle, C, having flanges a , a perforated bottom, and valves D D', hinged below the flanges and adapted to fit the inter-

ior seats, $d d'$, of the main pipe A, substantially as set forth.

In testimony that I claim the foregoing as my invention I have signed my name in presence of two subscribing witnesses.

GEO. A. REICH.
